[57] CLAIM

The design for a telephone stand, substantially as shown and described.

DESCRIPTION

FIG. 1 is a front perspective view of a desk telephone stand showing our new design;

FIG. 2 is a side elevation thereof, the opposite side being a mirror image of the side shown;

FIG. 3 is a rear elevation thereof;

FIG. 4 is a top plan view thereof;

FIG. 5 is a front elevation thereof;

FIG. 6 is a side elevation of a second modified embodiment of the stand disclosed in FIG. 1, the opposite side being a mirror image of the side shown;

FIG. 7 is a front elevation thereof;

FIG. 8 is a rear elevation thereof;

FIG. 9 is a top plan view thereof;

FIG. 10 is a side elevation of a third embodiment of the stand shown in FIG. 1, the opposite side being a mirror image of the side shown;

FIG. 11 is a front elevation thereof;

FIG. 12 is a rear elevation thereof;

FIG. 13 is a top plan view thereof; and

FIG. 14 is a cross-sectional view taken along line 14—14 in FIG. 13.
